UNITED STATES PATENT OFFICE.

WILLIAM ALEXANDER, OF LONDON, ENGLAND.

ROTARY ENGINE.

1,000,316.

Specification of Letters Patent. Patented Aug. 8, 1911.

Application filed June 15, 1910. Serial No. 567,000.

To all whom it may concern:

Be it known that I, WILLIAM ALEXANDER, a subject of the King of Great Britain, and resident of 4 Rosenau Crescent, Battersea, 5 London S. W., England, engineer, have invented certain new and useful Improvements in and Relating to Rotary Engines, of which the following is a specification.

This invention relates to fluid pressure engines (motors, pumps, compressors, blowers and the like) of the rotary type in which there is an inner revolving or rotative drum, within an outer rotative drum or casing and in which abutments, hinged to the drum 15 or the casing, are arranged to move in the spaces between the inner and outer drums.

My improvements consist in dispensing with an outer fixed casing, the outer drum being preferably used as a driving drum to 20 or from which the power is applied or taken, and in providing in such an engine a multiplicity of either hinged abutments or rigidly attached flexible abutments, a driving connection between the inner and outer 25 drums in the form of a link or by means of friction, and a cranked hollow axle or axles. In a modification the power may be applied to or taken from the inner drum.

These improvements have for their object 30 the simplifying of the drive; the reduction of wear, internal friction and leakage; the maintenance of practically a constant fluid flow of large volume, and the production of a compact rotary plant.

35 In my improved rotary engine the outer cylindrical drum or casing is revoluble and within it rotates on a parallel axis a revolving drum with abutments either hinged or rigidly attached thereto.

40 The speed of rotation of the outer casing is arranged to be the same as for the inner revolving drum either by means of a connecting link (which does not act as a hinged abutment) connected to both rotat-

45 tive members at opposite ends respectively, and acting as a driving connection between them, or by means of a frictional drive between them. The connecting piece may be flexible and rigidly attached at its ends or 50 it may be a bar hinged at the ends to the casing and the inner revolving drum respectively.

Several hinged abutments and two rotating members—the inner and outer rotat- 55 tors, are better as regards wear, friction, and

leakage than the corresponding features in other machines, with a fixed casing. By applying the driving power to or taking it from the external drum direct without the intervention of a shaft and pulley, the drive 60 is simplified and rendered more efficient. Also, in the type of machine in which there are two rotative drums, several abutments are better than one in that a much larger 65 quantity of fluid is dealt with per revolution and flow is more steady.

In order to minimize friction between the drums and their respective bearings the latter have been made small. This has been accomplished by providing a cranked hollow 70 axle or axles.

In the drawings attached hereunto:—Figure 1 is a transverse section through the inner and the outer drums. Fig. 2 is a longitudinal section thereof, and Fig. 3 shows a 75 plan of the hollow axle. Fig. 4 shows a section of a modified machine, the section being taken through the axes of the drums, showing ports arranged in the outer drum, and Fig. 5 shows a cross section at right 80 angles thereto.

The outer drum 1 is rotatably mounted on a hollow cranked axle 2 gripped or fastened in the standards 3. The inner revolving drum 4 is rotatably mounted on the cranked portion 5 of the axle which has a diaphragm 6 for separating ports 7 and 8 which register with the passages 9 communicating with the spaces 10 inclosed between the inner and the outer drums and successive pairs of abutments 11. The abutments are rotatably connected or hinged to the inner drum and, due to centrifugal force, press at their other ends against the surface of the outer drum so that 90 there can be little leakage past them. The friction between the outer drum and the free ends of the abutments is sufficient when the fluid pressure is low to insure the inner drum being rotated along with the outer 95 one.

When pressures are higher packing rings 12 (shown in Fig. 2) act on in a direction parallel to their axes by springs 13, are provided in the flat surfaces of either the inner or the outer drums to prevent leakage between the two latter and for the purpose of 105 providing a certain amount of frictional drive between them. When the pressures are higher still the two drums are positively connected by means of a link 14 (shown 110

dotted in Fig. 1) which is hinged to both, or by means of a flexible abutment rigidly fixed to both drums.

As rotation takes place the spaces 10 alternately increase and diminish in volume so that fluid is continuously taken from the suction portion 15 of the hollow axle outward through the passages 9 to fill the spaces 10, and then forced inward through 10 the same passages, at a different part of the revolution, and sent continuously to the delivery portion 16 of the axle.

There is a split liner 17 in the inner drum to enable the latter to be mounted in place 15 on the axle. In order to prevent leakage at the bearing 18 the space 19 is put in communication with the low pressure portion 15 of the axle by means of a channel 20 through the split liner and a passage 21 20 through the side of the axle.

Instead of fluid entering and leaving the axle at opposite ends of the axle respectively, it may be arranged to enter and leave at the same end by providing a longitudinal 25 diaphragm in the axle extending from the ports at the inner drum to the open end of the axle. The other portion of the axle would then be dispensed with and the two drums would overhang from one bearing. 30 Again, instead of the passages 9 being arranged in the inner drum, passages 22 may be arranged in the outer drum, in which case the axle can be in separate pieces 23, 24 as shown in Figs. 4 and 5.

35 The drive is effected by means of the power being applied to or taken from the outer drum direct when there are two bearings 18 and 25 as in Fig. 1, but when there is only one bearing, the power can be applied to either the inner or the outer drum. 40 In the case where the inner drum receives or delivers the driving power, in the case of

a pump or motor respectively, it is preferable that there should be no positive connection between the drums.

The constructive details, such as packings, mode of driving or others may be varied, and I do not confine myself to those herein described.

Claims—

1. In a rotary engine, the employment in combination with a revolving drum eccentrically disposed within a rotative casing, of means for dividing the space inclosed between the inner and outer drums, said means 55 consisting in a plurality of abutments hinged to the revolving drum, and means for delivering fluid to the said space, said means consisting in a cranked hollow shaft and passages in said revolving drum.

2. In a rotary engine, the employment in combination with a revolving drum eccentrically disposed within a rotative casing, of means for dividing the space inclosed between the inner and outer drums, said means 65 consisting in a plurality of abutments hinged to the revolving drum, a link hinged on the revolving drum and to the rotative casing, and means for delivering fluid to said space, said means consisting in a 70 cranked hollow shaft and passages in said revolving drum.

3. In a rotary engine, a hollow crank shaft, a revolving drum mounted on the shaft, a second drum mounted in the first 75 drum on the crank of the said shaft, a plurality of abutments carried by one drum and engaging the other, and a connecting link hinged to the said drums.

WILLIAM ALEXANDER.
